UNITED STATES PATENT OFFICE

112,344

DESIGN FOR A SHOE

Albert W. Lutz, Brockton, Mass., assignor to Geo.
E. Keith Company, Campello, Mass., a corpora-
tion of Massachusetts

Application October 12, 1938, Serial No. 80,405

Term of patent 3½ years

To whom it may concern:

Be it known that I, Albert W. Lutz, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side elevation of the same. Both

sides of the shoe present substantially the same appearance. The upper quarters are stippled so as to show a contrast in color with the unstippled portions of the shoe.

As the design is applicable to shoes of various shapes and styles the representation of shoe is merely conventional, for showing an application of the design.

I claim:

The ornamental design for a shoe, as shown and described.

ALBERT W. LUTZ.
